ATTYS.

UNITED STATES PATENT OFFICE.

LEE S. CHADWICK, OF CLEVELAND, OHIO, ASSIGNOR TO THE CLEVELAND FOUNDRY COMPANY, OF CLEVELAND, OHIO, A CORPORATION OF OHIO.

DESIGN FOR A WATER-HEATER CASING.

47,685.

Specification for Design.

Patented Aug. 10, 1915.

Application filed February 6, 1915. Serial No. 6,597. Term of patent 14 years.

To all whom it may concern:

Be it known that I, LEE S. CHADWICK, a citizen of the United States, residing at Cleveland, in the county of Cuyahoga and State of Ohio, have invented a new, original, and ornamental Design for a Water-Heater Casing, of which the following is a specification, reference being had to the accompanying drawing, forming part hereof, wherein—

Figure 1 is a front elevation, and Fig. 2 a side elevation of the water heater casing exhibiting my new design.

I claim:—

The ornamental design for a water heater casing as shown.

LEE S. CHADWICK.
